Frank S. Woodrow, Inventor
By his Attorney, Thomas A. Hill

UNITED STATES PATENT OFFICE.

FRANK S. WOODROW, OF NEW YORK, N. Y.

INJECTION DEVICE.

Application filed March 22, 1926. Serial No. 96,437.

My invention relates to improvements in injecting devices, and more particularly has reference to a form of magazine dart adapted to be shot into the skin of an animal and thereby automatically injecting a liquid adapted to render the animal unconscious for a short period of time. The dart is adapted more particularly for use with an air pistol or rifle, and is especially adapted 10 for the use of naturalists in procuring specimens of live animals.

Air guns, pistols, and rifles adapted to shoot such darts are generally well known, and therefore reference hereinafter will be 15 made only to the form of dart adapted for the purpose stated.

In the accompanying drawings, I have illustrated in Fig. 1, upon an enlarged scale, in side elevation, a suitable form of dart embodying an application of my invention. Fig. 2 is a longitudinal section of the same. Fig. 3 illustrates modifications.

3 indicates the entering portion or shell of a hollow dart which is preferably charged 25 with formic acid, the virus of hornets, or other suitable liquid adapted when injected into the body to produce temporary paralysis, the same being indicated by reference character 11. Upon the circular ledge 4, 30 within the dart is compressed the spiral spring 5, the other end of which is seated in the piston 6, and 7 is a circular depression adapted to form a seating for the piston on one side, and at the other side a seating 35 for the hair 8 which may be glued in position or held by other suitable means. The point 9 of the dart is provided with a small hole through which the liquid is ejected after the dart has penetrated the skin, the 40 impact of the dart causing the weighted piston 6 to travel toward the point of the dart against the action of the spring 5, which is compressed simultaneously with the ejection of the fluid.

45 To prevent possible leakage of the fluid through the opening in the point of the dart, the point may be plugged with paraffine wax, or other suitable material, to provide a stoppage in the point, as indicated at 10, 50 and the same will be readily discharged therefrom as the liquid is ejected. Of course, if desired, instead of paraffine wax, other suitable material may be used, and may be rendered poisonous or medicated ac-

cording to requirements, and the fluid may 55 be used only as a vehicle of injection. The particular material used for injecting will of course be varied according to the purposes and uses of the dart. For instance, for target practice, black ink or other suitable 60 staining material may be used, so that when the target is struck at a distance, the mark will be plainly visible, and in fact, various other modifications may be made in the construction and arrangement of parts, without departing from the spirit of the invention as claimed.

Referring more particularly to Fig. 3, it will be observed that the dart is provided with a hypodermic needle 12, the body portion 13 being hollow except for the virus or other liquid contained therein. Instead of the hair brush 8, as a tail to the dart, a plug 14, slightly larger in diameter than the diameter of the shell 13, may be employed, 75 preferably of soft metal, so as to engage the bore of the pistol or rifle, and if desired may be made of soft material, as upon impact of the dart it will be forced forwardly 80 through the shell, thereby ejecting the fluid 85 through the needle, and for that purpose, if desired, the shell itself may be made of soft material adapted to yield to the passage of the plug 14. Darts such as shown in Fig. 3 may be preferably for use upon animals 90 having a thick fur or skin, or where other outer covering is to be penetrated, and for this purpose the needles and plugs may be made interchangeable and of different sizes, weight, proportion, etc., thereby adapting 95 the darts for various uses.

Of course it will be understood that various modifications may be made in the construction and arrangement of parts without departing from the spirit of the invention as 95 claimed.

I claim:—

1. In an injecting device of the class described, a hollow shell terminating in a point, a hole through said point, and means 100 in combination with said shell for controlling the same in flight, liquid within said shell adapted when injected into an animal to cause temporary paralysis, and means within said shell adapted to inject said liquid upon impact thereof.

2. In an injecting device of the class described, a hollow shell terminating in a point,

a hole through said point, and means in combination with said shell for controlling the same in flight, and a hypodermic needle secured in said hole.

5 3. In an injecting device of the class described, a hollow shell terminating in a point, a hole through said point, and means

in combination with said shell for controlling the same in flight, and a hypodermic needle secured in said hole, and a soft metal ¹⁰ plug secured in the other end of said shell.

In testimony whereof I hereunto affix my signature.

FRANK S. WOODROW.
